US0D1055606S

(12) United States Design Patent (10) Patent No.: US D1,055,606 S
(45) Date of Patent: * Dec. 31, 2024

(54) ARMREST

(71) Applicant: VICCARBE HABITAT, S.L.,
Beniparrell (ES)

(72) Inventor: Victor Carrasco Berlanga, Valencia
(ES)

(73) Assignee: VICCARBE HABITAT, S.L.,
Beniparrell (ES)

() Term: 15 Years

(21) Appl. No.: 29/849,970

(22) Filed: Aug. 16, 2022

(30) Foreign Application Priority Data

Feb. 17, 2022 (EM) 008661231-0020

(51) LOC (14) Cl. 06-06

(52) U.S. Cl.

USPC D6/716.2

(57) CLAIM

The ornamental design for an armrest as shown and described.

DESCRIPTION

FIG. 1 is a perspective view of an armrest showing the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom view thereof.

The portions of the article shown in broken line form no part of the claimed design.

1 Claim, 7 Drawing Sheets
